UNITED STATES PATENT OFFICE.

CHARLES SAUNDERS, OF PHILADELPHIA, PENNSYLVANIA.

DESIGN FOR HEEL-PLATE FOR BOOTS AND SHOES.

Specification forming part of Design No. 5,997, dated July 16, 1872.

SPECIFICATION.

To all whom it may concern:

Be it known that I, CHARLES SAUNDERS, of Philadelphia, in the county of Philadelphia and State of Pennsylvania, have invented a certain new Design for Heel-Plate for Boots and Shoes; and I do hereby declare that the following is a full, clear, and exact description thereof, reference being had to the accompanying drawing and to the letters of reference marked thereon which form a part of this specification.

The nature of my design is fully illustrated by the accompanying drawing, in which the part marked *a* is a plane surface. The center

b of the heel-plate is sunken below the surface *a*, except the diagonal cross-bars *d d*, which are continuations of the surface *a* upon the sunken part *b*.

What I claim, and desire to secure by Letters Patent, is—

The design for heel-plate, substantially as shown and described.

In testimony that I claim the foregoing as my own invention I affix my signature in presence of two witnesses.

CHARLES SAUNDERS.

Witnesses:

JOSEPH SAUNDERS,
HARRY REEVES.
